UNITED STATES PATENT OFFICE.

HENRY H. LAMPERT, OF CHICAGO, ILLINOIS.

REINFORCING MEANS FOR CONCRETE-BEAM STRUCTURES.

Application filed March 5, 1927. Serial No. 173,106.

This invention relates to reenforcing systems for concrete construction work, and particularly to reenforcing systems adapted for use in connection with structural beams and 5 the like.

The main objects of this invention are to provide an improved form of reenforcing rod for use in systems of this kind; to provide improved means for spacing the reenforcing 10 rods from the structural element to permit them to be embedded in the soffit; and to provide improved fastening means for holding the reenforcing rods in substantially parallel spaced relation to each other and for securing 15 them to the structural element.

Illustrative embodiments of this invention are shown in the accompanying drawings, wherein:—

Figure 1 is a fragmentary perspective of a 20 structural beam, to which one of the improved reenforcing means is applied.

Fig. 2 is an enlarged end elevation of the same, the dotted outline showing one of the fingers in its upright position prior to being 25 bent over the flange of the beam.

Fig. 3 is a perspective of the reenforcing means.

Reenforcing systems embodying this invention may be used in connection with various 30 structural shapes, but, in the specific forms herein shown, they are adapted for use in connection with an I-beam 1, around which the concrete is poured for making girders, joists and the like.

35 In the form shown the device comprises a pair of reenforcing rods 2, which are spot welded or otherwise secured to a plurality of transverse tie wires 3. The distance between the rods 2 is considerably less than the width 40 of the beam flange so that, when the device is applied to the beam, the rods 2 are spaced inwardly from the side edges of the flange, as shown in Fig. 2.

In order to space the greater portion of the 45 reenforcing device from the structural element, the rods 2 are provided with crooks or spacers 4 arranged at certain intervals.

The tie wires 3 are arranged so as to permit the two reenforcing rods 2, to have a limited 50 relative movement toward and away from each other to accommodate structural elements of various widths. In the form shown, the tie wires are arranged in pairs with the wires of each pair crossed but not

connected together at their medial portions. 55 With this improved arrangement of parts, the flexibility of the tie wires 3 permits a limited relative movement of the rods 2 for lateral adjustment.

The tie wires 3 project laterally beyond the 60 reenforcing rods 2, so as to provide fingers 5 adapted to be bent over the beam flange for supporting the reenforcing device.

It is believed that the operation and method 65 of installing the improved devices herein shown and described will be obvious from the foregoing description.

Although but certain specific embodiments 70 of this invention have been herein shown and described, it will be understood that certain 75 details of the construction shown may be altered or omitted without departing from the spirit of this invention as defined by the following claims.

I claim:

1. A reenforcing device for use in connection with a structural element comprising a pair of substantially parallel reenforcing rods, and a pair of tie wires crossed and relatively movable at their medial parts and connected to said rods at points removed from said medial parts whereby said parallel rods have a limited relative movement toward and away from each other. 75

2. A reenforcing device for use in connection with a structural element comprising a pair of substantially parallel reenforcing rods, and a pair of tie wires crossed and free at their medial parts and connected to said rods at points removed from said medial parts 80 whereby said parallel rods have a limited relative movement toward and away from each other. 85

3. A reenforcing device for use in connection with a structural element comprising a pair of substantially parallel reenforcing rods having crimps formed therein to provide spacers for spacing said rods from the element, a plurality of transverse tie wires 3 arranged in pairs and welded to said rods, the wires of each pair being free and crossed at their medial parts whereby said parallel rods have a limited relative movement toward and away from each other, and fingers formed on said wires for attachment to the element. 95

Signed at Chicago this 3rd day of March 100 1927.

HENRY H. LAMPERT.
